UNITED STATES PATENT OFFICE.

HARRY VAUGHN, OF JAMAICA, NEW YORK.

DESIGN FOR A BOTTLE.

53,324.

Specification for Design.

Patented May 13, 1919.

Application filed October 6, 1917. Serial No. 195,201. Term of patent 14 years.

To all whom it may concern:

Be it known that I, HARRY VAUGHN, a citizen of the United States of America, residing at Jamaica, on Long Island, in the county of Queens and State of New York, have invented a new, original, and ornamental Design for Bottles, of which the following is a specification, reference being had to the accompanying drawing, forming part thereof.

The figure is a perspective view of a bottle showing my new design.

I claim:

The ornamental design for a bottle as shown.

In testimony whereof I affix my signature.

HARRY VAUGHN.
